United States Patent Office

Des. 195,683
Patented July 16, 1963

195,683

TRAY

Jens H. Quistgaard, Meggen, Lucerne, Switzerland, assignor to Dansk Rare Wood Company, Inc., Great Neck, N.Y., a corporation of New York

Filed Dec. 7, 1962, Ser. No. 72,763

Term of patent 14 years

(Cl. D44—10)

FIG. 1 is a top plan view of a tray, showing my new design;

FIG. 2 is a side elevational view thereof;

FIG. 3 is a bottom plan view thereof; and

FIG. 4 is a side elevational view thereof as viewed looking toward the corner of the design on the diagonal.

I claim:

The ornamental design for a tray, as shown.
